UNITED STATES PATENT OFFICE.

EDWARD SPENCER BRADBURY, OF CHRISTCHURCH, NEW ZEALAND.

FASTENER FOR GARMENTS AND THE LIKE.

1,273,725.

Specification of Letters Patent.

Patented July 23, 1918.

Application filed December 10, 1915. Serial No. 66,050.

To all whom it may concern:

Be it known that I, EDWARD SPENCER BRADBURY, a citizen of the Dominion of New Zealand, and residing at Rolleston street, 5 Linwood, Christchurch, in the Provincial District of Canterbury, in the Dominion of New Zealand, have invented certain new and useful Improvements in Fasteners for Garments and the like, of which the following is a specification.

This invention relates to devices used for fastening garments and for analogous purposes such as attaching curtains to curtain rings.

15 The fastener consists of two parts, one part comprising arms united by a bow or coil spring, hook terminations upon the arms, and grip members upon the arms for facilitating the pressing of the hooks together. When used upon a garment this said part is secured to one flap of a coat or other garment by means of a loop of leather or other material stitched or otherwise secured to the said garment. The loop and 25 spring are covered by material similar to the material of the garment.

The other part of the fastener comprises a D shaped ring secured by a loop, similar to the loop of the first part, to the opposite 30 flap of the coat or garment to be fastened. This said loop and the rear part of the D shaped ring are covered by the material of the garment. The straight side of the D shaped ring terminates in recesses into 35 which the hook terminations of the first part of the fastener enter and are securely held.

The drawing herewith illustrates the invention and will be referred to for the purposes of a detailed description.

40 Figure 1, is a front elevation, and Fig. 2, a plan of the fastener attached to the flaps of a garment.

Fig. 3, is an elevation of the D shaped ring, and

45 Fig. 4, is an elevation of the fastener as used for attaching a curtain to a curtain ring.

The fastener is conveniently made of wire, and comprises a first part having arms 50 1 and 2 united by a bow or coil spring 3, and terminating in hooks 4 and 5, which are splayed outwardly. Grip members 6 and 7 are formed by bending the wire of the arms upon itself and forming outward projec-

tions, which can be readily gripped. Instead of making the grips integral with the arms as described, they may be made separately and secured to the arms by soldering or otherwise. The hooks have their ends 8 bent over in order to prevent the said ends 55 from catching when the coat or other garment is unfastened.

The said first part is secured to the flap 10 of the garment by a loop 11 of leather or other material stitched or otherwise secured 60 to the said flap.

The loop 11, the spring 3 and part of the arms 1 and 2 are protected or hidden by a covering 12 made of the same material as used in making the garment.

70 The second part of the fastener comprises a D shaped ring 13. The ends of the straight side 14, where they join the bow part of the ring, are formed into recesses 15 and 16. The ring 13 is secured to the flap 16 of the garment by a loop 17 of leather or other material, which is stitched to the said flap. The loop 17 and the rear part of the ring 13 are protected or hidden by a covering 18 made of the same material as used in 75 making the garment.

The fastener can be made of any suitable material, such as steel or hard brass wire or the like, and is so formed that when in use the hooks 4 and 5 are sprung into position 85 within the ring 13 and are locked in the recesses 15 and 16 by the force of the spring 3 and by the splaying of the hooks.

When connecting together the two parts of the fastener, the grip members 6 and 7 90 are pressed together until the hooks 5 and 6 are close enough to pass into the ring 13. The spring 3 is then allowed to force the hooks into the recesses 15 and 16. To separate the two parts the grip members are 95 again pressed together to release the hooks from the recesses.

Although a leather loop is preferable for securing the fastener to the garment, the same may be attached directly to the garment by stitching or by other suitable means.

In Fig. 4 the ring 13 is attached to a curtain ring 20 by an eyelet 21, and a curtain safety pin 22 is connected by its loop 23 to 105 the spring 3. The curtain 24 is attached to the safety pin in the ordinary way.

The fastener can be used in any desired

size to suit heavy or light garments, and supersedes the ordinary button, or hook and eye.

What I do claim and desire to secure by 5 Letters Patent of the United States is:—

1. A fastener of the kind described, consisting of a member having a pair of substantially parallel arms joined at one end by a spring coil and having their other ends 10 bent outwardly away from each other, and another member comprising a substantially straight portion transverse to said arms and an open circular portion; the ends of said straight portion being inwardly curved to 15 partially surround the last mentioned ends of the first member and being joined to the ends of the circular portion by reversely curved portions.

2. A fastener of the kind described, con-

sisting of a member having a pair of substantially parallel arms joined at one end and having their other ends bent outwardly away from each other, and another member comprising a substantially straight portion 20 transverse to said arms and having its ends curved inwardly around the ends of the arms of the other member and then reversely curved to coact with the ends of the arms of the first member during relative movement of said members to facilitate disengagement of the same. 25

In testimony whereof I have signed my name to this specification in the presence of two witnesses:

EDWARD SPENCER BRADBURY.

Witnesses:

H. P. BRIDGE,

T. A. J. HART.

Copies of this patent may be obtained for five cents each, by addressing the "Commissioner of Patents, Washington, D. C."
